UNITED STATES PATENT OFFICE.

CHARLES LEE, OF SAN ANTONIO, TEXAS.

FIST-BLOW TESTER.

SPECIFICATION forming part of Letters Patent No. 600,481, dated March 8, 1898.

Application filed March 20, 1897. Serial No. 628,521. (No model.)

To all whom it may concern:

Be it known that I, CHARLES LEE, a subject of the Queen of Great Britain, residing at San Antonio, in the county of Bexar and 5 State of Texas, have invented a new and useful Fist-Blow Tester, of which the following is a specification.

This invention relates to machines for testing the force of a blow delivered by a person's fist, and has for its object to provide a simple, durable, and efficient machine embodying a striking-cushion for receiving the impact of the blow, recording mechanism for indicating the precise force of the blow, and 15 coin-operated apparatus for releasing the striking-pad preparatory to delivering the blow, the device being thus automatic in action.

Other objects and advantages of the invention will appear in the course of the ensuing description.

The invention consists in a fist-blown-testing machine embodying certain novel features and details of construction and arrangement 25 of parts, as hereinafter fully described, illustrated in the drawings, and incorporated in the claims.

In the accompanying drawings, Figure 1 is a side elevation of the improved machine, 30 partly in section, with the adjacent side of the casing removed. Fig. 2 is a front elevation of the machine, showing the indicator. Fig. 3 is a plan view of the machine with the top removed. Fig. 4 is a horizontal section 35 on the line xx of Fig. 1.

Similar numerals of reference designate corresponding parts in the several figures of the drawings.

Referring to the drawings, 1 designates the 40 inclosing case of the machine, which is substantially in the form of a rectangular box. At its rear the case is provided with a surrounding flange 2, which is perforated at intervals to receive fasteners by means of which 45 the machine may be secured to a wall or other suitable support, and at one side the casing is provided with a hinged door 3 for giving access to the internal mechanism. Arranged in the lower portion of the case is a tubular 50 plunger 4, which slides through the front wall of the case and also through a guide 5 there-

in. This plunger is provided, preferably at its top, with a longitudinal guiding-rib 6, which slides through a notch or slot in the guide 5 and prevents the plunger from turning. At its outer end the plunger 4 is provided with a rigid metal plate 7, to the outer surface of which is secured a disk or block of wood 8. Outside of the block 8 is arranged a rubber pad 9, and outside of said pad 9 is 55 a cushion 10, comprising a soft flexible covering 11 and a filling 12 of hair, cotton, wool, or similar material for cushioning the blows delivered thereto and preventing injury to the knuckles and the hands. Intermediate 60 its ends the plunger 4 is provided with an internal annular flange 13, forming a shoulder for a plate or disk 14, against which is seated one end of a spiral compression-spring 15, arranged partly within the plunger and 65 extending beyond the inner end thereof, the opposite end of said spring being seated in a recess in a block 16, attached to the rear wall of the casing 1.

17 designates a cross-pin which passes transversely through the plunger adjacent to the annular flange 13, the ends of said pin projecting outside of the plunger and being provided with washers 18, of rubber or analogous material, which serve as bumpers, the same 80 coming in contact with shoulders 19, at or near the front wall of the case, for limiting the outward movement of the plunger and cushioning the same when thrust outward by the expansive force of the spring 15. 85

20 designates a latch pivotally connected at one end to the block 16 or other convenient point adjacent to the rear wall of the case and provided at its free end with a shoulder 21 for engaging the rib 6 of the plunger and 90 preventing the inward movement of the latter. The latch 20 also has a lip 22, which rests on the rib 6, and is further provided with an inclined bottom edge or face 23, against which the rib 6 operates in the inward movement of 95 the plunger for elevating the latch. A rod 24 connects loosely at its lower end to the latch 20 and at its upper end to the rear end of a lever 25. This lever is fulcrumed intermediate its ends on a bracket 26, located near 100 the top of the case, and is provided at its forward end and in its upper surface with a cav-

ity 27 for receiving the coins from an angular chute 28, projecting above the top wall of the case and secured for convenience thereto.

29 is a weighted pin arranged in the path 5 of the rear end of the lever 25 and slidably mounted in an arm 30 on the bracket 26. As the forward end of the lever 27 is depressed by the weight of the coin resting in the cavity 27 the rear end of said lever strikes against 10 the pin 29 and is stopped temporarily thereby, the latch 20 being lifted sufficiently to move the shoulder 21 out of the path of the plunger. When the plunger is thrust forcibly inward by the blow delivered thereon, the rib 15 6 acts against the inclined surface 23 of the latch and thrusts upward on the rod 24, thereby depressing the forward end 27 of the lever 25 and precipitating the coin into a sub-posed receptacle 31, arranged inside of the 20 case.

32 designates a horizontal spindle journaled in the front wall of the case and in the upper portion of the bracket 26. This spindle is arranged at one side of the coin-chute 28 25 and is provided near the front of the case and inside of the same with a drum or pulley 33, having a beveled rear flange 34 and a square-faced forward flange 35. A cord or other flexible connection 36 is fastened at one end 30 to said drum and is wound around the same, and the other end of said cord passes around a guiding-pulley 37 and connects to the plunger 4 or its rib 6, as shown. The spindle 32 extends through the front wall of the case 35 and has a hand or indicating-finger fast upon it, said hand being adapted to revolve in front of a graduated dial 38 and to register the force of the blow delivered upon the plunger.

39 is a spring-brake which bears against the 40 periphery of the flange 35 and prevents the indicating hand or finger being carried beyond the proper point by the sudden jerk on the cord or connection 36.

In operation a coin is deposited in the chute 45 28 and the same falls into the cavity 27 of the lever 25, depressing the front end of the latter and elevating its rear end so as to elevate the latch 20 sufficiently to remove the same from the path of the plunger. The blow is 50 now struck upon the plunger, and the force of said blow is received and absorbed by the spring 15, and at the same time the latch 20 is thrust upward and the rear end of the lever 25 lifts the pin 29, allowing the front end of 55 said lever to descend and deposit the coin in the receptacle 31. As the plunger is forced inward the cord 36 is drawn upon and the drum 33 rotated under the resisting influence of the spring-brake 39, the indicating hand 60 or finger being at the same time rotated to a point corresponding to the distance to which the plunger was thrust inward.

The machine is exceedingly simple in construction, reliable in operation, and will accurately register the force of a blow delivered 65 upon the plunger.

It will be understood that the several parts

of the machine are susceptible of changes in the form, proportion, and minor details of construction, which may accordingly be resorted to without departing from the spirit or sacrificing any of the advantages of this invention.

Having thus described the invention, what is claimed as new is—

1. In a fist-blown-testing machine, a plunger, and a compression-spring for resisting the movement thereof, in combination with a metal plate secured to one end of said plunger, a wooden block secured to said plate, a pad of rubber forming a facing for said block, and a cushion arranged in front of said rubber pad and comprising a flexible cover and a filling of fibrous material, substantially as described.

2. In a fist-blown-testing machine, the combination with a plunger carrying a striking-pad, and a cushion-spring for said plunger, of a gravity-latch engaging directly with said plunger and arranged to ride thereon and to be sustained in a raised position thereby during the sliding play of the plunger, and a coin-free mechanism operatively connected with said latch, substantially as described, for the purposes set forth.

3. In a fist-blown-testing machine, the hollow plunger provided with an internal shoulder and with protruding pins or studs, combined with a coiled compression-spring partially fitted in the plunger and seated at one end against the internal shoulder of the plunger and at its other end in a suitable support, yieldable bumpers mounted on the protruding pins or studs and movable with said plunger, fixed abutments in the path of said bumpers, and a coin-free latch arranged to engage operatively with the plunger, substantially as described, for the purposes set forth.

4. In a fist-blown-testing machine, the combination of a casing having a plunger-receiving opening, a stationary guide 5 within said casing and in alignment with said opening in the front thereof, a tubular plunger provided on its exposed face with a longitudinal guide-rib and fitted slidably in the openings in the casing and said guide, a disk 13 fixed within the plunger, the latter carrying the exposed yieldable bumpers, a cushion-spring fitted against said disk 13 and seated in the casing, a latch to restrain the plunger from endwise movement, and a coin-controlled releasing device connected with said latch, as and for the purposes described.

5. In a fist-blown-testing machine, the combination with a spring-controlled plunger carrying a striking-pad, of a gravity-latch arranged to engage with said plunger to lock the same and to ride upon the plunger to be sustained in a raised position thereby, a coin-operated lever pivoted at a point intermediate 130 of its length and adapted to receive at its free end a coin to overbalance the same and lift the latch, a link attached to the short arm of said lever and to the latch and affording a

connection to hold the free end of the lever in a depressed position when the latch is lifted by engagement with said plunger, and a slideable gravity-pin in the path of the short arm 5 of said coin-operated lever to resist the movement thereof, the resistance of said pin being overcome by the upward thrust of the latch and link, substantially as described, for the purposes set forth.

10 6. In a fist-blow-testing machine, a plunger having a striking-pad, and a spring for resisting the movement of said plunger, in combination with a pivoted latch for engaging and holding said plunger, and adapted to ride

15 thereon when the plunger is forcibly impelled inwardly, a coin-operated lever provided with a coin-receptacle, connections to said latch for moving the latter out of engagement with the plunger, and a gravity-pin for resisting the

20 movement of said lever, said latch having an inclined face against which the plunger acts for forcibly lifting the latch and tilting the coin-operated lever against the weight of the gravity-pin, substantially as and for the purpose described.

25 7. In a fist-blow-testing machine, the combination with a casing, a dial, and a spindle carrying a pointer, of a spring-cushioned plunger provided with a guide-rib and with a striking-pad, a pulley attached to the spindle, a

30 guide-sheave between the spindle and plunger, a flexible cord coiled on the spindle-pulley, passing around the guide-sheave and attached to the guide-rib on the plunger, a gravity-latch 35 hung to engage with and to ride upon said guide-rib of the plunger, and a coin-free mechanism operatively connected with said latch, substantially as described, for the purposes set forth.

40 8. In a fist-blow-testing machine, the combination with a plunger, and a cushion-spring therefor, of a gravity-latch hung to engage directly with said lever to normally restrain

it from inward movement and, when disengaged from locking engagement therewith, to 45 ride upon said lever on its inward movement, a coin-operated lever positively linked at one end to said latch and provided at its other end with a coin-receptacle, and a gravity-pin lying in the path of said lever to temporarily 50 arrest its tilting movement under the gravity of a coin deposited therein, whereby the forcible inward movement of the plunger lifts the latch and link to tilt the coin-operated lever against the resistance of the gravity-pin and 55 thereby discharge the coin from the receptacle on said lever, as and for the purposes described.

9. In a fist-blow-testing machine, a spring-resisted plunger carrying a striking-pad, a 60 latch for engaging and holding said plunger and provided with an inclined face adapted to rest on and to ride upon said plunger when the latch is freed from locking engagement therewith, a coin-actuated lever linked to the 65 latch and adapted to move the same out of engagement with the plunger, a coin-chute arranged over said lever, a coin-receptacle carried by said lever, a gravity-pin in the path 70 of said lever to limit the upward movement thereof on the deposit of a coin in its receptacle and arranged to be lifted by a tilting movement of the lever as the latch and link are raised on the inward movement of the plunger, a revoluble indicator, a drum on the 75 spindle of said indicator, a cord wound around said drum and attached to the plunger, and a spring-brake for resisting the momentum of the indicator, substantially as described.

In testimony that I claim the foregoing as 80 my own I have hereto affixed my signature in the presence of two witnesses.

CHARLES LEE.
